PROCESS AND APPARATUS FOR THE SEPARATION OF FIBROUS AND
NONFIBROUS MATERIALS

Filed Nov. 1, 1922

UNITED STATES PATENT OFFICE.

KURT GERSON, OF BERLIN, GERMANY.

PROCESS AND APPARATUS FOR THE SEPARATION OF FIBROUS AND NONFIBROUS MATERIALS.

Application filed November 1, 1922. Serial No. 598,336.

To all whom it may concern:

Be it known that I, KURT GERSON, a citizen of the German Republic, and resident of 107 Gitschner Str., Berlin, Germany, 5 have invented certain new and useful Improvements in Processes and Apparatus for the Separation of Fibrous and Nonfibrous Materials, of which the following is a specification.

10 This invention relates to the separation of confused materials, particularly garbage, into its fibrous and non-fibrous constituents. Heretofore it has been the usual practice in connection with the separation of garbage, 15 and of confused material in general, to conduct the material between rollers with the object of crushing the hard constituents and simply compressing the fibrous materials, which are then separated by sifting. As a 20 single passage through such crushing mills has not proved sufficient, it has become necessary to carry out the process of separation in stages by consecutively passing the material between coarse crushing and fine 25 crushing rollers and subsequently sifting it. This way of separation, however, has great disadvantages in that the installations therefor are costly and cumbersome, and that considerable volumes of dust are set free 30 which are very injurious to the health of the workmen. In spite of all, the separation could never be completed properly as the finest particles had to be removed by currents of air which were just sufficiently 35 strong to remove any vegetable powder but not the fine mineral dust.

The main object of the invention, therefore, is a new process by which the aforesaid disadvantages are entirely obviated and in 40 which the separation into crushable and compressible materials may be carried out in one single stage.

A further object of the invention is the provision of a device for carrying out the new process, which shall be efficient in use 45 and entirely automatic in action, and of which the costs of production and maintenance are exceedingly low.

With these and other objects in view the 50 process forming part of the invention consists in the separation of the garbage into its fibrous and non-fibrous constituents within a dust-proof casing by continuously crushing and grinding the materials upon a 55 crushing path in such a manner, that the

fibrous materials do not become strained but simply compressed, whereas all hard constituents are broken up and completely disintegrated. The said process may be carried out by simultaneously heating the materials 60 so as to extract all moisture therefrom and thereby aid the process of crushing.

According to the invention the new process is carried out within a device which operates substantially in the manner of a 65 pug mill or other known crushing mill, by runners being rotated upon a crushing path, the materials being treated slowly in one single stage and until all hard ingredients are finely crushed. Scrapers are provided 70 to scrape all materials from the crushing path onto a shaking sieve to be sifted and removed from the device, whereby the finely crushed parts leave the device through the preferably hopper-like bottom, whilst the 75 fibrous parts are swept beyond the sieve into a discharge opening provided in the casing. The grinding path may be provided with heating means so that, if desired, the process of crushing and separating may be 80 assisted by the application of heat.

The accompanying drawing illustrates the invention by way of example.

Fig. 1 is a vertical section through the centre of the device, parts being shown in 85 elevation.

Fig. 2 is a plan view of the crushing path and sieve partly broken away and showing also the scrapers which are used for moving the materials.

Fig. 3 shows two detail views of the scrapers.

Fig. 4 shows the means for shaking the sieve.

In the example shown in the drawing a 95 particular form of crushing mill is provided, which ensures a slow, even and careful action on the fibrous materials without stretching or tearing the fibres. As will be seen, conical runners A are provided to circulate over a 100 crushing path B, and owing to the fact that the apices of the cones A are positioned in the plane of the crushing path, the same velocity prevails at all point of contact between the runners and the crushing path, 105 so that a grating or straining action on the material, such as would undoubtedly be the case in any ordinary crushing mill, is rendered impossible. The runners A are mounted for rotation on inclined shafts A', 110

which are pivoted at their inner ends, as at D to the upper end of a vertical shaft D' on which is secured a beveled gear C''. A horizontal shaft C³ is provided at the outer end 5 with fast and loose power pulleys, one of which is indicated at C, and at the inner end with a beveled gear C⁴ which engages the gear C''. A charging tube E is provided through which the product is admitted 10 into the device. If the product is sufficiently dry it may be treated directly, but if moist materials are to be treated it is advisable to construct the crushing path in the form of a heating plate by making it 15 hollow, for example, and providing radiators or heating coils such as are indicated at B¹ in the drawing. Scrapers F¹, F² and F³ are arranged to move the materials over the working surfaces; the scraper F¹, which 20 extends from the centre of the device to the edge of the crushing path, serves to move the material into the path of the runners as it is fed through the tube E. Scraper F² circulates over the crushing path and the 25 sieve, whereby it is in contact with the said path but moves over the sieve with a moderate amount of clearance as shown in the upper view of Fig. 3; it serves to conduct the material from the crushing path 30 onto the sieve, thereby sweeping any fibrous materials over the outer edge of the sieve into the discharge tube G. All such parts of the garbage which have been completely desintegrated by the action of the runners 35 fall directly through the meshes of the sieve S whilst the coarser parts are caught by the scraper F³, which may be integral with the scraper F², but constructed to be in contact with the surface of the sieve, and are returned 40 onto the crushing path in order to be again subjected to the action of the rollers.

For the purpose of facilitating the sifting of the materials the sieve S is provided with 45 shaking means such as a lever S¹ pivotally mounted at its centre as at S⁴ on supporting member S⁵, and the lower arm of which is acted upon by a cam S², on the shaft C³ whilst its upper arm is slotted and in contact 50 with a pin S⁶ held by brackets S⁷ on the lower surface of the sieve, a spring S⁸ being provided to keep the lower arm in contact with its actuating cam.

The entire device is enclosed within a 55 dust-proof casing I which is provided with one or more ventilation openings K. If de-

sired, these ventilation openings may lead into a suction conduit for the removal of the dust.

What I claim is:—

1. Method of separating mixtures which contain fibrous compressible but not crackable ingredients as well as crackable ingredients, as for instance, refuse, waste, sweepings, consisting in first subjecting the material to a slowly acting comminuting operation, removing the uncomminuted fibrous material while the crackable material is being comminuted, sifting the comminuted material remaining after the removal of the uncomminuted matter, and resubmitting to such comminuting action such crackable material as may have escaped comminution.

2. Method of separating mixed fibrous and comminutable material, such as garbage, consisting in subjecting the same to pressure-grinding action to grind the comminutable particles, removing the fibrous particles during such pressure, grinding action, and resubmitting such removed comminutable particles as may have escaped comminution to such pressure grinding action.

3. Device for separating ingredients of mixtures, which mixtures consist of fibrous ingredients and comminutable ingredients, comprising a closed casing having a central feed pipe, a grinding plate and runners arranged to operate on the grinding plate and 85 of conical form, the apices of the roller being arranged in the plane of the guiding plate, in combination with an annular sifting surface surrounding the grinding surface and with a plurality of rotatable 90 scrapers which slide over the grinding surface and sifting surface.

4. Device as set forth in claim 3, characterized by a casing, a central feed pipe, a grinding plate and conical runners and also 100 having an annular sifting surface, including a plurality of scrapers one of which extends from the feeding pipe to the inner edge of the grinding surface another being arranged to scrape over the grinding surface and sifting surface, and to touch with its lower edge the grinding surface only, and the third scraper being arranged to pass only over the sifting surface and to engage with its lower edge said sifting surface.

In witness whereof I affix my signature.
KURT GERSON.
